E. L. AIKEN

TERMINAL POST

Filed August 3, 1925

INVENTOR
EDWARD L. AIKEN

BY
A. D. T. Libby
ATTORNEY

UNITED STATES PATENT OFFICE.

EDWARD L. AIKEN, OF EAST ORANGE, NEW JERSEY.

TERMINAL POST.

Application filed August 3, 1925. Serial No. 47,995.

To all whom it may concern:

Be it known that I, EDWARD L. AIKEN, a citizen of the United States, residing at East Orange, in the county of Essex, State 5 of New Jersey, have invented certain new and useful Improvements in a Terminal Post, of which the following is a description, reference being had to the accompanying drawing, and to the figures of reference 10 marked thereon.

This invention relates to a terminal post for use in connection with electrical apparatus and it is the principal object of my invention to provide a terminal post to 15 which electrical connections may be quickly made.

Another object of my invention is to provide a terminal post which will take either a straight wire, terminal, or the ordinary 20 spade clip commonly used in electrical circuits such as are found in telephone and radio work.

Another object of my invention is to provide a terminal which is simple in construction, cheap to manufacture, yet one that will provide a good electrical contact and hence be efficient in operation.

My invention will be best understood by reference to the drawing in which—

30 Figure 1 is an assembled view on an enlarged scale of the terminal post attached to a mounting plate and showing a spade clip held by the terminal.

Figure 2 is a section on the line 2—2 of 35 Fig. 1 with the plunger depressed.

Figure 3 is a view of the push button part of the terminal post.

In the drawing 1 is a thimble having slots 2 and 3 substantially diametrically opposite. 40 Mounted within the thimble 1 is a push button or plunger 4 having an end protruding through the other part of the thimble. The plunger 4 has a pair of annular flanges 5 and 6 spaced apart so as to provide an annular groove 7. The plunger 4 is normally held by the spring 8 so the flange 5 is against the spun over portion 9, at the upper end of the thimble 1. When in this position the flange 6 closes the slots or grooves 45 2 and 3 thereby keeping dust and dirt out of the thimble.

As shown in Fig. 1 the plunger 4 has been depressed a certain amount so that a spade clip 10 can be inserted through the slots 2 and 3, straddling the portions 11 of the thimble and the spade clip 10 is gripped be-

tween the flange 6 and the wall of the thimble 1. It will be observed that spade clips of varying thickness may be inserted across the slots 2 and 3. It will also be 60 observed that a straight terminal or a conducting wire itself may be passed straight through the slots 2 and 3 and the annular groove 7, on, either or both sides of the stem portion 12, or, the wire may be attached to 65 the terminal post by laying it edgewise in either one of the slots 2 or 3, the same as one side of the spade clip. It will also be seen that both the spade clip and a straight terminal or wire may be simultaneously 70 used. The thimble 1 is preferably provided with an integral stem 13 which is threaded for the purpose of attaching same to the mounting plate as by means of nuts 15.

Having thus described my invention what 75 I claim is:

1. A terminal post comprising; a thimble having means for mounting, said thimble having a pair of substantially opposite horizontal slots cutting through the wall 80 of the thimble, a plunger held within the thimble but having an end protruding therefrom, said plunger having a pair of flanges disposed to form an annular groove therebetween of substantially the width of 85 the thimble slot and a spring within the thimble cooperating with the thimble to normally hold the plunger so the lower flange thereon closes the slots in the thimble.

2. A terminal post comprising; a thimble 90 having means for mounting, said thimble having a pair of substantially opposite horizontal slots cutting through the wall of the thimble, a plunger held within the thimble but having an end protruding 95 therefrom, said plunger having a pair of parallel flanges spaced from each other a distance sufficient to take the ordinary spade clip or wires of varying diameters within a given range and which may be 100 passed through the slots in the thimble and a spring within the thimble acting against the inner end of the plunger.

3. A terminal post comprising; a thimble having means for mounting, said thimble 105 having a pair of substantially opposite horizontal slots cutting through the wall of the thimble to a distance such that the space between the slots is such as to allow a standard spade clip to bridge the thimble, a plunger held within the thimble but having an end protruding therefrom, said 110

plunger having at least one flange adapted to normally close the slots but to grip the spade clip after the plunger has been moved so the spade clip can be inserted in the 5 slots and a spring within the thimble acting on the plunger for the purpose described.

4. A terminal post comprising; a thimble having means for mounting, said thimble 10 having a pair of substantially opposite horizontal slots cutting through the wall of the thimble, a plunger held within the thimble but having an end protruding therefrom, said plunger having a pair of 15 spaced flanges arranged so that when the plunger is depressed the space between the flanges may be brought into alignment with said slots whereby a straight conductor may be passed all the way through the 20 thimble between the flanges or a spade clip may be passed across the slots between the flanges and a spring within the thimble to react on the plunger to cause either the conductor or clip to be gripped between one 25 of said flanges and the thimble.

5. A terminal post comprising; a thimble having means for mounting, said thimble having a pair of substantially opposite horizontal slots cutting through the wall of 30 the thimble, a plunger held within the

thimble but having an end protruding therefrom, said plunger having a pair of parallel horizontal flanges, the lower of which normally closes said slots in the thimble, the distance between the flanges being substantially the width of the slots so that when the plunger is depressed a spade type terminal may be caused to bridge the thimble between the flanges or a straight conductor may be passed clear through the 40 thimble or across one slot in the side of the thimble between said flanges and a spring within the thimble to react on the plunger to cause either the conductor or clip to be gripped between one of said flanges and the 45 thimble.

6. A terminal post comprising; a thimble having means for mounting, said thimble having a pair of oppositely disposed parallel arcuate slots in the wall thereof, a plunger held within the thimble but having an end protruding therefrom, said plunger having a pair of flanges disposed to form an annular groove substantially parallel to said slots and preferably at least as wide as the 50 slots and a spring within the thimble and cooperating therewith to normally react on the plunger.

In testimony whereof I affix my signature.

EDWARD L. AIKEN.
